UNITED STATES PATENT OFFICE.

SARAH HARRIS, (NOW BY MARRIAGE SARAH ROSENTOWER,) OF NEW YORK, N. Y.

COLLAR.

1,039,528.

Specification of Letters Patent. Patented Sept. 24, 1912.

Application filed January 29, 1909. Serial No. 475,065.

To all whom it may concern:

Be it known that I, SARAH HARRIS, (now by marriage SARAH ROSENTOWER,) a citizen of the United States, and a resident of the city of New York, borough of Manhattan, in the county and State of New York, have invented a new and Improved Collar, of which the following is a full, clear, and exact description.

10 This invention relates to collars, and more particularly to a stiff collar fashioned from linen, celluloid, rubber, paper or other material and having a button-hole adapted to receive a collar-button to hold the collar in place when it is being worn, the collar further having the button-hole connected by means of a slit or line of severance, with an edge of the collar, so that the collar-button can be inserted in the button-hole by forcing 15 20 25 the shank of the button inwardly from the edge of the collar, along the slit to the button-hole, by forcing aside the flap formed by the button-hole and the slit or in any other convenient manner.

25 The object of the invention is to provide a collar having button-holes into which the collar-button can be easily inserted and from which it can be as easily removed, which obviates the usual difficulty and annoyance 30 35 40 sides injury and wear to the collar itself occasioned by the operation of putting on and taking off the ordinary collar.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a perspective view of a collar having an embodiment of my invention applied thereto and showing the collar buttoned by means of a collar-button of the usual type; Fig. 2 is an enlarged perspective view of the tabs or ends of the collar having the button-holes; Fig. 3 is a similar view showing a tab of a collar having applied thereto an embodiment of my invention, of modified form; and Fig. 4 is a view similar to Fig. 3 and showing another modified form.

Before proceeding to a more detailed explanation of my invention it should be clearly understood that while the same is

particularly useful in connection with collars usually worn by men, women and children, it can also be advantageously applied to any other articles of apparel which are 60 stiffened by starch or the like or which are fashioned from linen, celluloid, rubber, paper or other material and which are held in place by buttons inserted through button-holes. Needless to say, the annoyance often 65 occasioned in buttoning a collar is generally known. The difficulty is usually caused by the fact, that because of the stiffness of the collar it is extremely difficult to insert the collar-button into the button-hole, and the 70 process of stiffening, furthermore, often causes the edges of the button-holes to adhere to each other.

My invention is designed to avoid the difficulty of buttoning a collar, and permits the 75 collar-button to be introduced into the button-hole by a simple manipulation.

Referring more particularly to the drawings, 10 represents a collar having the collar tabs or ends 11 provided with button-holes 12.

It will be understood that my invention can be applied to any type of collar and that any form of button-hole which is elongated longitudinally of the band can be 85 used therewith. The form of button-hole shown herewith, has at one end an enlargement 13 which receives and tends to hold the shank of the collar-button. The button-holes are connected by slits or lines of 90 severance 14 through the material, with edges 15 of the collar tabs at points removed from the ends of the tabs. The terminals 16 and 17 of the slits are preferably rounded, and the slits themselves may be at any desired angle with the length of the button-holes. The latter, with the slits, form flaps 18 which may be displaced to permit the button to be easily introduced into the button-hole. Again, the collar-button can be 100 inserted in the button-holes by forcing it inwardly from the edge, along the slits, to the button-holes.

In Fig. 3 I have shown a collar 19 having a button-hole 20 and a slit 21 arranged at a 105 different angle from the corresponding slits 14. In Fig. 4, furthermore, I have shown a collar 22 having a button-hole 23 and a slit 24 which is different again, from the slit 21. The slits 14 are inclined from their respective button-holes toward the free ends of the tabs. The slit 21 is inclined away from 110

the free end of the collar tab, while the slit 24 is directed at substantially right angles from the button-hole toward the edge of the tab. I prefer to have the slits join the button-holes at the ends of the button-holes remote from the free ends of the tabs, as obviously, the collar-button normally rests, when the collar is closed, at the opposite ends of the button-holes, that is, at the ends nearer the free extremities of the tabs.

10 The invention is more especially applicable to collars having a turnover top with a flap or tab on the end of the band adapted to underlie the top of the opposite end of the band. By having the entrance passage leading from the lower edge of the band to the hole for the button shank, when the flap or tab has been engaged with the button, and inserted under the turnover top, the tab end 15 will be held securely. Furthermore, by having the hole for the button shank elongated longitudinally of the band, the end of the collar may be positioned correctly after the button shank reaches the hole and even after 20 the tab end has been placed in position under the opposite end of the turnover top, the structure in this respect resembling in action a collar having the usual button hole and which, as well known, is adapted to be 25 drawn up by the tie, if slightly large for the shirt band, or if it is desired, to have 30

the ends of the turnover top, or in case of a standing collar, the vertical edges close together.

Having thus described my invention, I 35 claim as new, and desire to secure by Letters Patent:—

1. A collar having a band and overlapping end tabs with substantially straight button shank receiving holes therein, elongated longitudinally of the band, and a passage in one of said tabs formed by a slit extending from the said button shank receiving hole to the lower edge of the tab at a point removed from the end of the tab. 40 45

2. A collar having a band and overlapping end tabs with substantially straight button shank receiving holes therein elongated longitudinally of the band and a passage in one of said tabs formed by a slit extending from the inner end of the shank receiving hole to the lower edge of the tab at a point removed from the end of the tab, said slit having closely contiguous substantially straight edges. 50 55

In testimony whereof I have signed my name to this specification in the presence of two subscribing witnesses.

SARAH HARRIS.
